Application March 1, 1946, Serial No. 127,009

Term of patent 14 years

(Cl. D81—19)

To all whom it may concern:

Be it known that we, George Schueder and Walter Dorwin Teague, citizens of the United States, residing, respectively, in Dearborn, Wayne County, Michigan, and New York, N. Y., have invented a new, original, and ornamental Design for a Heating Apparatus, of which the following is a specification, reference being had to the accompanying drawing, forming a part thereof, wherein:

Fig. 1 is a perspective view showing the front and one side of a heating apparatus embodying my new design; and

Fig. 2 is a perspective view showing the top, front and other side thereof.

We claim:

The ornamental design for a heating apparatus, substantially as shown.

GEORGE SCHUEDER.

WALTER DORWIN TEAGUE.
